DIRIGIBLE AUXILIARY ROADLIGHT

Filed July 2, 1925

UNITED STATES PATENT OFFICE.

FRANK A. PAYNE, OF CALISTOGA, CALIFORNIA.

DIRIGIBLE AUXILIARY ROADLIGHT.

Application filed July 2, 1925. Serial No. 40,985.

To all whom it may concern:

Be it known that I, FRANK A. PAYNE, a citizen of the United States, residing at Calistoga, in the county of Napa and State of California, have invented certain new and useful Improvements in Dirigible Auxiliary Roadlights, of which the following is a specification.

This invention relates to auxiliary lights for automobiles, and more particularly to roadlights of a dirigible character adapted for mounting upon one of the fenders at one side of the machine, preferably the left, or driver's, side, and positioned to focus its rays on the right-hand side, or edge, of the road, forwardly and slightly downwardly to strike at substantially 31 feet in advance of the machine.

The light proper is suitably mounted to revolve about its support and is connected through a plurality of levers and rods to the pull-rod of the steering mechanism in such manner that any movement of the steering-wheel, as in changing direction or rounding a curve, will move the light correspondingly to properly focus its rays to the changing course of the roadway.

The mounting of the device to normally focus its light rays upon the right-hand side of the roadway greatly facilitates night driving and serves in large measure to prevent the attendant glare being directed toward an approaching machine in such manner as to blind its driver and rendering possible additional accidents through collisions.

A primary object of the invention is the provision of a road-light of the character described that is efficient, of cheap and simple construction, and one that may be readily applied to any make of automobile and automatically operated through movement of the steering-gear.

Another object is the provision of a light of the character described that normally directs its light rays to the right-hand side of the roadway and at an established distance in advance of the machine bearing it.

A further object is the provision of a device of the character specified, in which are provided connection of a universal character permitting utmost freedom of movement therebetween, thus largely eliminating friction and increasing greatly its efficiency.

Other objects and advantages will appear

with reference to the subjoined specification and one sheet of drawings, in which—

Figure 1 is a top plan view of an automobile, showing the position of the light and normal direction of its rays focussed upon the right-hand side of the roadway and at a fixed distance in advance of its machine;

Figure 2 is an enlarged perspective view of the forward end of an automobile, showing the method of mounting the supporting-post bracket to the underside of the left-hand fender and the actuating connections therefor connected to the pull-rod;

Figure 3 is a top plan view of the light-supporting post-bracket and actuating connections, a fragmentary section of the automobile being shown to assist in locating the device;

Figure 4 is a side elevation, showing the light and mounting bracket, as secured to a fragment of the fender, and, also, the method of mounting the reduction-lever to the vehicle chassis.

Figure 5 is an enlarged sectional detail of the light-supporting post and attaching bracket;

Figure 6 is a sectional detail of the reduction-lever and attaching means to the vehicle chassis, this section being indicated on the line 6—6 of Figures 3 and 4; and

Figure 7 is an enlarged sectional detail of one of the universal joint connections, taken on line 7—7 of Figure 4.

Referring more particularly to the drawings, it will be noted with reference to Figures 2 and 4, that the device is best adapted for attachment to the underside of the left-hand fender of the vehicle by means of an attaching bracket 1 bolted securely to the fender guard 2, by means of bolts 3, the lower end of the bracket being provided with a bolt opening adapted to receive a clamping bolt 4 for the attachment thereto of supporting bracket 5 adapted for lateral adjustment with respect to said attaching bracket. The supporting bracket 5 carries a horizontally extending section 6 provided

at its outer end with a boss 7 provided with a centrally disposed tapped opening 8 adapted to receive the lower threaded end 9 of the supporting-post sleeve 10 held rigidly in place by means of a jam-nut 11. A spindle 12 fits within the sleeve 10, with the upper end 13 extending above the upper

edge of the sleeve and its lower end 14 squared and fitted into a short rocker-arm lever 15 and adapted for free rotary movement within said sleeve. The upper end of said spindle is fitted with a clamping member 16, open at one side and provided with ears 17 adapted to receive clamping bolts 18, which, when drawn up tightly, embrace the upper end 13 of the spindle and maintain the light-holding member 19 in adjusted position, said light-holding member having an opening 20 and a set-screw 21 adapted to receive and clamp the extension 22 of the light 23 in place, thereby connecting the light 23, light-holding member 19, clamping member 16 and spindle rigidly together, as a unit adapted to swing freely in a horizontal plane with respect to the sleeve 10. As is shown in Figures 3 and 4, the light 20 is adjusted to cant both downwardly and to the right, so that its rays will be focussed substantially at a point on the right-hand side of the roadway and distant some 31 feet in advance of the vehicle. The means for actuating the light and light-spindle in unison with the movement of the steering-wheel comprise a reduction lever 24 mounted at the side of the chassis frame 25 by a bolt 26 and held in place upon said bolt by a cotter-pin 27, the upper short end 28 of said lever being connected to the rocker-arm lever 15 by a rod 29 and universal-joint connection 30, the lower end being adapted for connection to the pull-rod clamp 31 by a rod 32 and universal-joint connection 33. The pull-rod clamp 31 comprises a pair of plates 34 and 35 shaped to embrace the pull-rod 36 of the steering-gear and is adapted to be tightly clamped thereto by means of bolts 37 and 38, with the upper end of the plate 34 extending above the plate 35 and carrying a stud 39 adapted to bear a universal-joint connection 33. The universal-joint connections 32 and 33 adapt the device to different adjustments and provide for a flexibility in operation insuring positive and dependable action. The thrust of the pull-rod may be varied to suit requirements, by adjusting the rod 32 to any

one of a plurality of openings 40 in the 50 lower end of the lever 24.

It may be stated, as a matter of interest, that this device has been, as required, submitted to tests at the University of California and favorably reported upon, and this 55 report later acted upon and approved by the motor vehicle department of the State of California.

Having thus described my invention, I claim, and desire to secure by Letters Patent:

In a device of the character described, the combination with an automobile and its steering mechanism, of a lamp supporting-post comprising a sleeve bearing a revoluble 65 spindle, said spindle extending beyond the upper end of said sleeve and provided with a squared lower end, a supporting-bracket for said post, an attaching-bracket adjustably secured to said supporting-bracket and 70 adapted for mounting to the underside of the fender on the steering side of the vehicle, a rocker-arm lever mounted upon the squared lower end of said spindle, a clamp member bearing a lamp mounted upon the 75 upper end of said spindle adjacent the upper end of said sleeve, said lamp being normally adjusted to cant both downwardly and to the right to focus its rays substantially at a point 31 feet in advance of the vehicle and 80 to the right-hand side of the roadway, and actuating means connecting said rocker-arm lever and the steering mechanism, comprising a reduction lever mounted upon the vehicle chassis bearing adjustment openings 85 in its lower end, a clamp-member mounted upon the pull-rod of said steering mechanism, a link connection between said rocker-arm lever and reduction lever bearing a universal-joint connection, and a link connection 90 between said reduction lever and said pull-rod clamp-member bearing a universal-joint similar to the aforementioned universal-joint.

In testimony whereof I have affixed my 95 signature.

FRANK A. PAYNE.
